US00D934632S

(12) **United States Design Patent** (10) **Patent No.:** **US D934,632 S**
Gross et al. (45) **Date of Patent:** **** Nov. 2, 2021**

(54) **CUTTING DEVICE FOR A NUT MILK MAKER**

(71) Applicant: **Eternal East (HK) Ltd.**, Hong Kong (CN)

(72) Inventors: **Charles Brian Gross**, Cheyenne, WY (US); **Nile Robert Fedewa**, Ft Collins, CO (US)

(73) Assignee: **ETERNAL EAST (HK) LTD.**, Hong Kong (CN)

(**) Term: **15 Years**

(21) Appl. No.: **29/726,896**

(22) Filed: **Mar. 6, 2020**

Related U.S. Application Data

(62) Division of application No. 29/665,580, filed on Oct. 4, 2018, now Pat. No. Des. 877,577, which is a division of application No. 29/616,513, filed on Sep. 6, 2017, now Pat. No. Des. 878,847.

(57) **CLAIM**

The ornamental design for a cutting device for a nut milk maker, as shown and described.

DESCRIPTION

FIG. 1 is a front perspective view of a cutting device for a nut milk maker.

FIG. 2 is a front elevation view of FIG. 1.

FIG. 3 is a back elevation view of FIG. 1.

FIG. 4 is a left side elevation view of FIG. 1.

FIG. 5 is a right side elevation view of FIG. 1.

FIG. 6 is a top plan view of FIG. 1; and,

FIG. 7 is a bottom plan view of FIG. 1.

The broken lines in the drawings depict portions of the cutting device for a nut milk maker that form no part of the claimed design.

1 Claim, 6 Drawing Sheets
